FEELER-MOTION FOR LOOMS

1,292,989.

Specification of Letters Patent.

Patented Feb. 4, 1919.

Application filed March 7, 1917. Serial No. 153,162.

To all whom it may concern:

Be it known that I, EUGENE H. BALLOU, a citizen of the United States, residing at Pawtucket, county of Providence, and State 5 of Rhode Island, have invented an Improvement in Feeler-Motions for Looms, of which the following description, in connection with the accompanying drawings, is a specification, like characters on the drawings repre-

10 resenting like parts.

The invention to be hereinafter described relates to feeler motions for looms, whereby, when the filling in the shuttle has become substantially but not completely exhausted, 15 a train of mechanism is rendered effective to change the operative condition of the loom. This change in the operative condition of the loom may and usually does result in replenishment of filling, either by 20 the substitution of a shuttle containing a working supply of filling for the one in which the filling has become substantially exhausted, or by replacing the filling carrier or bobbin in the shuttle, by one having a 25 fresh supply of filling thereon.

In that type of feeler motions wherein the feeler has a detecting movement relative to the filling carrier or bobbin in the shuttle when the filling becomes substantially exhausted, 30 but is held from such detecting movement by engagement of the feeler with the filling on each detecting beat until substantial exhaustion is reached, it is important that the feeler engage the filling on 35 each detecting beat with sufficient pressure to enable the filling to hold the feeler from detecting movement so long as a working supply is present in the shuttle. It is also essential that the feeler partake of its detecting movement when the critical point of 40 filling exhaustion occurs, otherwise the loom may continue to run until the filling is completely exhausted and cause a defect in the cloth by a partial pick of filling being laid 45 in the shed.

An important feature of the present invention, therefore, consists of a feeler and means permitting the feeler to engage the filling on each detecting beat with sufficient pressure to enable the filling to hold the 50 feeler from detecting movement so long as a sufficient supply of filling is present to continue the weaving operation, but acting to relieve the pressure of the feeler against

the filling or bobbin when the filling is substantially exhausted. In carrying this feature of the invention into practical effect, the means for controlling or relieving the pressure of the feeler against the filling or bobbin is rendered effective by engaging a 55 part carried by the lay, when, by reason of the depletion of filling the feeler enters further into the shuttle.

The feeler is illustrated in the present instance of the invention as of the rotary type 60 and has connected thereto a part which causes initiation of filling replenishment or other change in the loom condition when, on a detecting beat of the lay, the feeler is rotated or rocked about its longitudinal axis. 65

Other important features of the present invention in addition to those above-noted will be hereinafter described in connection with the accompanying drawing showing one good form of means for carrying the 70 invention into practical effect, it being understood that details may be varied without departing from the true scope of the invention as defined by the claims.

In the drawings:

Figure 1 is a plan view of a feeler mechanism containing the present invention;

Fig. 2 is a cross-section on the line 2—2 of Fig. 3;

Fig. 3 is a side elevation of the feeler 75 mechanism, with the casing or stand shown in section.

The feeler stand or support may be of any desired construction suitable for sustaining the parts of the feeler motion, and in the 80 present instance of the invention comprises a stand 1 which may be appropriately secured to the loom frame or other support by suitable means, such as the bolts 2* which pass through the usual elongated slots provided in the side portion of the feeler stand. 85

Mounted on the feeler stand 1 is a slide 2, which, for purposes of identification, may be termed the relieving slide. The relieving slide 2 is under the influence of a spring 3, 90 which, in the present instance of the invention, surrounds the stem of the slide within the feeler stand and has one end resting against the inner front wall of the feeler stand and the other against a shoulder 3* 95 formed on the slide, the construction being such that the spring normally acts to hold the relieving slide 2 in rearward position, 100 105

substantially as indicated in Figs. 1 and 3. The relieving slide 2 is preferably flattened rearwardly of the spring 3 and has an upwardly extending portion 4 from which side pieces 5 project rearwardly. The rear portions of the side pieces 5 are connected by a bridge 15 in which is adjustably mounted the contact member 6 adapted at times to be engaged by a part carried by the lay to move 10 the relieving slide forwardly against the force of the spring 3, for a purpose that will presently appear.

The feeler stand carries the feeler which is adapted to feel for the filling in the 15 shuttle on a detecting beat and be moved forwardly thereby. In addition to its forward movement, the feeler has a detecting movement in a different direction, but is held from such detecting movement on each 20 detecting beat by engagement with the filling in the shuttle, until the filling is substantially exhausted and thereupon performs its detecting movement and initiates replenishment of filling. In the present instance 25 of the invention, the feeler comprises a part 8 mounted for longitudinal and rotative or rocking movement in the bearing 7 rising from the feeler stand and the bearing 7^x carried by the relieving slide 2. Extending 30 from the rear of the part 8 of the feeler is the part 9 from which projects the filling engaging end of the feeler having the teeth 10 or other roughened character.

Mounted upon the feeler is an arm 11 carrying a roller 12 which, when the feeler is 35 in its rearward position as indicated by Figs. 1 and 3, is adapted to rest upon the raised portion 14 of a track or guideway 13 and prevent rotative or rocking movement 40 of the feeler. The raised portion 14 and the track 13 are connected by an incline or cam surface 15'. In the present instance of the invention the arm 11 is connected directly to the part 8 of the feeler by the hub 45 portion 20 of the arm which may be adjustably secured to the part 8 by the set screw 21, and the arm has connected thereto or formed integral therewith the hook 16 adapted to engage a controller 17 and initiate 50 filling replenishment, when, on forward movement of the feeler, the arm 11 and 55 perforce, the hook 16 are turned or rocked into position to engage the controller, as will more fully appear.

55 The feeler is normally under the influence of a yielding means, such as a spring, for holding the feeler in rearward position with the roller 12 resting on the raised portion 14 of the track. In the present instance of 60 the invention, a spring 18 is mounted on the part 8 of the feeler, one end of the spring bearing against the hub portion 21 of the arm 11 and the other end against the bearing 7, the construction being such that the 65 spring normally acts to hold the feeler in its

rear position, as indicated in Figs. 1 and 3, with the toothed end of the feeler rearward of the contact member 6 and the rear end of the part 8 resting against the front surface 22 of the bridge 15.

70 When the parts are positioned as described, the filling engaging end 10 of the feeler will enter the shuttle on each detecting beat, and engage and sink into the filling and upon further forward movement of the lay, the feeler will be moved forwardly 75 against the yielding action of the spring 18, thereby moving the roller 12 from the raised portion 14 of the track 13, and the contact member 6 may then engage the front wall 80 of the shuttle or shuttle-box or other part mounted on the lay and also be moved to the front, according to the relative positions of the adjustable contact member and end 10 of the feeler. When a working supply 85 of filling is present in the shuttle, the spring 18 will cause the feeler end 10 to sink into the mass of filling with sufficient force to prevent rotative or rocking movement of the feeler about its longitudinal 90 axis when the roller 12 is moved from the raised portion 14 of the track, and the hook 16 will move to the front in a path of non-intersection with the controller. As the filling is drawn from the shuttle on each 95 succeeding pick, the mass of filling opposed to the feeler becomes progressively less and less and the feeler enters farther and farther into the shuttle, until, when the filling has approached or reached substantial exhaustion, the contact member 6 will engage the part carried by the lay and be moved forwardly in advance of the forward movement of the feeler, due to its engagement 100 with the filling or bobbin in the shuttle, and the feeler will be moved forwardly by the bridge 15 before the full force of the feeler spring 18 asserts itself against the filling or bobbins, thereby relieving the pressure of the feeler against the filling or bobbin and 105 insuring its detecting movement. Thus, during the presence of a working supply of filling in the shuttle on a detecting beat, the full force of the feeler actuating spring 110 is transmitted through the feeler to the filling and insures sufficient pressure of the feeler against the filling to hold the feeler from its detecting movement as the lay beats up, but when the filling has become substantially exhausted and it is desirable to have 115 the feeler perform its detecting movement to initiate filling replenishment, the pressure of the feeler against the filling or bobbin is relieved to an extent sufficient to insure detecting movement of the feeler.

120 In the present instance of the invention the detecting movement of the feeler is one of rotation or partial rotation about its longitudinal axis, so that, when the roller 12 is moved from the raised portion 14 of 125

the track and such movement is effected upon substantial exhaustion of filling in the shuttle, the hook 16 is moved into position to engage and actuate the controller 17 as the 5 feeler is moved to the front. The weight of the arm 11 may be sufficient to insure rotative movement of the feeler when the filling is substantially exhausted on a detecting beat, but this may be assisted in some 10 cases by giving to the spring 18 a torsional action tending also to turn or rotate the feeler. In such case one end of the spring at 23 may be secured to the hub of the arm 11 and the other end 24 to the fixed bearing 15 7, as indicated in Figs. 1 and 3.

After a detecting movement of the feeler and as it is moved rearwardly again into feeling position by the feeler spring, the roller 12 will ride up the incline 15 of the 20 track and rock or rotate the feeler to its initial or set position.

When the controller has been actuated to initiate filling replenishment, it should be reset or brought back to initial position, as 25 the feeler returns to feeling position as described, and to this end the relieving slide 2 has an arm 19 extending therefrom, which, as the said slide and feeler return to initial 30 position after an indication for replenishment, engages the controller 17, Figs. 2 and 3, and moves the controller to its initial position ready for another actuation by the feeler.

Claims:

- 35 1. In a feeler motion for looms, the combination of a feeler to feel for the filling in the shuttle and be moved forwardly as the lay beats up, means tending to rock the feeler about its longitudinal axis when it is moved forwardly and prevented from effecting such movement by engagement of the feeler with the filling until substantial exhaustion, feeler pressure relieving means adapted to engage a part movable with the lay for relieving the pressure of the feeler against the filling carrier on a detecting beat when the filling has approached substantial exhaustion, and means for preventing rocking movement of the feeler when it is in rearward position and becoming ineffective when the feeler is moved forwardly on a detecting beat.
- 40 2. In a feeler motion for looms, the combination of a feeler mounted for longitudinal and rotative movements and held from such rotative movement as it is moved longitudinally by engagement with the filling until substantial exhaustion thereof, a part mounted for movement forwardly independent of the feeler and adapted to move the feeler forwardly before the full feeler pressure is exerted in the filling carrier when the filling has reached a predetermined degree of exhaustion, and means for holding the feeler from rotative movement
- 45 when the feeler is in rear position and freeing the feeler to such rotative movement when away from the rear position.
- 50 3. A feeler motion for looms, comprising, in combination, a feeler mounted for rotative movement about its longitudinal axis, means normally tending to rotate the feeler on a detecting beat and held from effecting such rotative movement by feeler engagement with the filling until substantial exhaustion, means movable forwardly by engagement with the shuttle and acting to move the feeler forwardly to relieve the feeler pressure when on a detecting beat the filling has reached a predetermined degree of exhaustion, and means for preventing rotative movement of the feeler when in its rearward position and becoming ineffective when the feeler is moved forwardly.
- 55 4. A feeler motion for looms, comprising, in combination, a feeler adapted to feel for the filling in the shuttle on a detecting beat and be moved forwardly thereby, means normally tending to rotate the feeler about its longitudinal axis and prevented from effecting such movement by feeler engagement with the filling, means for preventing rotative movement of the feeler when in its rearward position and freeing it to rotative movement when the feeler is moved from rearward position, and a relieving member engaged by the shuttle and acting to move the feeler forwardly for relieving the pressure of the feeler against the bobbin in the shuttle when the filling is substantially exhausted on a detecting beat that the feeler may be rotated.
- 60 5. In a feeler motion for looms, the combination of the lay and shuttle-boxes, a feeler to engage and be moved forwardly by the filling in the shuttle on a detecting beat, means normally acting upon the feeler to rotate it about its longitudinal axis when it is moved forwardly and prevented from effecting such rotative movement by the pressure of the feeler against the filling until substantial exhaustion thereof, a relieving member, means normally acting to hold the relieving member in rearward position as the feeler is moved forwardly and operating to move the feeler forwardly when on a detecting beat the filling is substantially exhausted.
- 65 6. In a feeler motion for looms, a feeler, means tending to rotate the feeler about its longitudinal axis and prevented from effecting such movement by engagement of the feeler with the filling until substantial exhaustion, a feeler pressure relieving device movable forwardly independent of feeler movement and acting to move the feeler forwardly when the filling reaches a predetermined degree of exhaustion for relieving the pressure of the feeler against the filling or bobbin that the means tending to ro-

tate the feeler may be effective, and means controlled by the feeler for initiating filling replenishment.

7. In a feeler motion for looms, the combination of the lay, a feeler mounted for longitudinal and rotative or rocking movements and held from such rotative or rocking movement on a detecting beat of the filling in the shuttle when a working supply 10 is present, means for preventing rotative or rocking movement of the feeler when it is in rear or back position and freeing the feeler to rotative or rocking movement under control of the filling when the feeler is moved 15 away from rear or back position, means mounted for reciprocating movement independent of the feeler and adapted to be operated by a part on the lay for relieving the pressure of the feeler against the filling 20 when, on a detecting beat, the filling is substantially exhausted and the feeler is to be rotated or rocked.

8. In a feeler motion for looms, the combination of the lay, a feeler adapted to be moved frontwardly by the filling on a detecting beat, means tending to rotate the feeler when moved frontwardly and prevented from effecting such movement by the filling until substantial exhaustion thereof, 25 a relieving member, said feeler and relieving members being mounted for relative independent reciprocating movements, means for actuating the relieving member to relieve the pressure against the filling carrier, 30 when the filling is substantially exhausted that the means tending to rotate the feeler may be effective, and means for initiating filling replenishment.

9. In a feeler mechanism for looms, a 40 feeler having a rotary detecting movement but held from said detecting movement by engagement with the filling until substantial exhaustion thereof, a relieving member, said feeler and relieving member being 45 mounted for relative movement toward and from the front of the loom, a part carried by the relieving member to engage the feeler on a detecting beat when filling is substantially exhausted to relieve the pressure 50 sure of the feeler against the surface within the shuttle that the feeler may partake of its rotary detecting movement.

10. In a feeler motion for looms, the combination of a feeler adapted to be moved 55 frontwardly on a detecting beat and having a rotary detecting movement when the filling is substantially exhausted but held from said detecting movement by engagement with the filling in the shuttle until substantial exhaustion of filling has been reached, 60 means acting to yieldingly hold the feeler in rear position, and means mounted for reciprocating movement independent of the feeler and having a part rendered effective

by entrance of the feeler farther into the 65 shuttle when the filling is substantially exhausted to relieve the pressure of the feeler against the filling or bobbin under the impulse of the yieldingly acting means.

11. In a feeler motion for looms, the combination of a feeler adapted to be moved frontwardly on a detecting beat and having a rotary detecting movement when the filling is substantially exhausted but held from 70 said detecting movement by engagement 75 with the filling in the shuttle until substantial exhaustion of filling has been reached, a member movable toward the front of the loom on a detecting beat independently of the feeler, and a part actuated by said member 80 to move the feeler frontwardly before the full feeler pressure has been exerted against the filling or bobbin when the filling is substantially exhausted.

12. In a feeler motion for looms, the combination of a feeler adapted to be moved frontwardly on a detecting beat and having a rotary detecting movement about its longitudinal axis when the filling is substantially exhausted but held from 85 said detecting movement by engagement with the filling in the shuttle until substantial exhaustion of filling has been reached, a member mounted independent of the feeler, means for yieldingly forcing the said member rearwardly 90 but permitting it to be moved frontwardly on a detecting beat, said feeler and member having parts adapted to be engaged to effect movement of the feeler frontwardly before the full feeler pressure is exerted on the 100 filling or bobbin when, on a detecting beat, the filling is substantially exhausted.

13. In a feeler motion for looms, the combination of a feeler, means for turning the feeler about its longitudinal axis and prevented from effecting such movement on a detecting beat by engagement of the feeler with the filling until substantial exhaustion thereof, a track or guideway having a raised portion at the rear thereof, a roller connected to the feeler and traveling on said track or guideway, said roller preventing 105 rotative movement of the feeler when in rear position but freeing it to such movement when moved away from said position, 110 and means for initiating filling replenishment.

14. A feeler mechanism for looms, comprising, in combination, a feeler having a rotary detecting movement about its longitudinal axis, a relieving member mounted independently of the feeler and having a part against which the feeler may rest when in rearmost position and from which it is moved when a working supply of filling is 120 present on a detecting beat, and means carried by the lay for moving the relieving member frontwardly in advance of the 125

feeler on a detecting beat to cause said part to engage the feeler and move it frontwardly before the full feeler pressure is exerted against the carrier and permit rotary detecting movement of the feeler.

15. In a feeler motion for looms, the combination of a feeler adapted to be moved frontwardly on a detecting beat and having a rotary detecting movement but held from such detecting movement by engagement with the filling until substantial exhaustion thereof, a feeler pressure relieving member having a part to engage and move the feeler frontwardly before the full feeler pressure is exerted on the filling or bobbin when the filling is substantially exhausted, a controller actuated by the feeler when, on a detecting beat, the feeler detects substantial exhaustion of filling, and means movable by

the feeler pressure relieving member to return the controller to initial position.

16. A feeler mechanism for looms, comprising, in combination, a feeler having a reciprocating and a rotary movement, an arm projecting from the feeler and having a hook, a controller adapted to be actuated by the forward movement of the hook when the feeler is permitted rotary movement by substantial exhaustion of filling on a detecting beat to operatively position the hook, and means operating by return movement of the feeler to feeling position for returning the controller to initial position.

In testimony whereof, I have signed my name to this specification.

EUGENE H. BALLOU.
